JULIA LUKAS, OF NEW YORK, N. Y.

DESIGN FOR A TEXTILE FABRIC OR THE LIKE

Application filed December 8, 1932. Serial No. 46,324. Term of patent 3½ years.

To all whom it may concern:

Be it known that I, JULIA LUKAS, a citizen of the United States, residing at 321 West 74th Street, in the borough of Manhattan, city, county, and State of New York, have invented a new, original, and ornamental Design for a Textile Fabric or the like, of which the following is a specification, reference being had to the accompanying drawing, forming part thereof.

The figure is a surface view of a piece of textile fabric or the like, showing the de-

sign. The area within the dot and dash lines shows one complete unit of the design. The repeats are arranged in vertical rows and adjacent vertical rows are one half a complete unit offset so that the angle of the complete unit indicated by letter A corresponds with angle B of one of the repeats in an adjacent vertical row.

I claim:

The ornamental design for a textile fabric or the like, as shown and described.

JULIA LUKAS.
